UNITED STATES PATENT OFFICE.

HERMANN DEBOR, OF MUNICH, GERMANY.

SHELL-SHAPED BODY SUITABLE FOR THE ALLOWANCE OF HIGH-PRESSURE STRESSES.

Application filed January 21, 1927, Serial No. 162,664, and in Germany December 4, 1923.

The device in question refers to shell shaped bodies suitable for the allowance of high pressure stresses with the view of producing a shell shaped body, combined of several parts, to withstand higher pressures than the familiar shell shaped bodies, for instance steam boilers.

For this aim my device consists out of a shell-shaped body, the sectional area of which is a combination of chambers in sector form, arranged in a multiple number in a radial sense, as will be specified and claimed later on.

The device in question will be more readily understood by reference to the enclosed drawing, wherein represents:

Fig. 1 a sectional area of the shell shaped body;

Fig. 2 a partial cut on an enlarged scale.

Fig. 3 a partial cut on an enlarged scale, but braced in a different way.

The body according to Fig. 1 has been constructed out of chambers, the sectional area of which show the arrangement of sectors, connected to each other which are curve-shaped on the outside, with adjacent lying sides *b*, arranged in a radial sense.

In the middle of the several chambers a tubular space *c* is left free, into which a cylindrical ring *d* of suitable sectional area has been arranged. Space *c* is made absolutely tight in order to serve as a feed or drain for the matter contained in the chambers *a* or as heating or refrigerating pipe.

Since the pressure in all the chambers *a* is equally high, the longitudinal sides *b* are only under a stress of tension, arising through the pressure of the matter upon the inner and outer front plates *e* and *f* of the chambers *a*. As these sides are offering a relatively small working area the body shows a high resistance against internal pressures. This resisting force even with equal plate thickness is often higher, than for instance the resisting force of a single hollow-cylinder steam boiler or of a compressor-cylinder.

The precautions against the displacement of the chambers *a* in a radial sense are taken according to Figs. 1 and 2 through the ar-

rangement of dove-tailed rails, which on one side are catching in corresponding grooves *h* of the inner front plates *f* of the chambers *a*, and on the other side in corresponding grooves *i* of the cylindrical ring *d*.

55

Besides the advantage of the higher pressure-resisting-force, the device in question shows still the other advantage that is constructed out of a multiple number of parts, which are easily manufactured one by one and conveyed and also mounted and dismounted without the least difficulty.

60

What I claim is:

1. Shell-shaped body for matter as for instance air, gases, steam and so forth under high stresses or stresses to be raised, consisting of a multiple number of chambers, each being sector shaped in cross section and arranged radially and means preventing radial displacements.

65

2. Shell-shaped body for matter under high stresses or stresses to be raised, consisting of a multiple number of chambers, each being sector shaped in cross section and arranged radially, and curve-shaped on the outside.

70

3. Shell-shaped body for matter under high stresses or stresses to be raised consisting of a multiple number of chambers, each being sector shaped in cross section and arranged radially and forming a hollow space in the middle.

75

4. Shell-shaped body for matter under high stresses or stresses to be raised consisting of a multiple number of chambers, each being sector shaped in cross section and arranged radially and held against radially occurring displacements through dove-tailed connections.

80

5. Shell-shaped body for matter under high stresses or stresses to be raised consisting of a multiple number of chambers, each being sector shaped in cross section and arranged radially and braced on a centrally located ring through dove-tailed connections.
